CLAIM

The ornamental design for an elevated knife plate bracket, as shown and described.

DESCRIPTION

FIG. 1 is a top front left perspective view of an elevated knife plate bracket in accordance with the present invention. FIG. 2 is a top front right perspective view showing the elevated knife plate bracket of FIG. 1.

FIG. 3 is a bottom rear right perspective view showing the elevated knife plate bracket of FIG. 1.

FIG. 4 is a front elevation view showing the elevated knife plate bracket of FIG. 1, with the rear being a mirror image thereof.

FIG. 5 is a left elevation view showing the elevated knife plate bracket of FIG. 1, with the right being a mirror image thereof.

FIG. 6 is a top plan view showing the elevated knife plate bracket of FIG. 1; and,

FIG. 7 is a bottom plan view showing the elevated knife plate bracket of FIG. 1.

The broken lines shown in the Figures depict environmental subject matter only and are not part of the claimed design.

1 Claim, 6 Drawing Sheets
